UNITED STATES PATENT OFFICE.

HEINRICH HENRICH, OF NEW YORK, N. Y., ASSIGNOR TO ROSA HENRICH,
OF SAME PLACE.

FINGER-RING.

SPECIFICATION forming part of Letters Patent No. 278,959, dated June 5, 1883.

Application filed October 30, 1882. (No model.)

To all whom it may concern:

Be it known that I, HEINRICH HENRICH, of the city, county, and State of New York, have invented a new and useful Improvement in 5 Ornamenting Finger-Rings and other Articles of Jewelry, of which the following is a full, clear, and exact description.

Reference is to be had to the accompanying drawings, forming part of this specification, in 10 which similar letters of reference indicate corresponding parts in all the figures.

Figure 1 is a front elevation of a ring to which my improvement has been applied. Fig. 2 is a side elevation of the same. Fig. 3 15 is a side elevation of the ring before the side pieces are applied. Fig. 4 is a front elevation of the same, showing one side piece applied and in section. Fig. 5 is a sectional elevation of one of the side pieces. Fig. 6 is a view 20 showing the outer side of one of the side pieces. Fig. 7 is a view showing the inner side of the same. Fig. 8 is a sectional view of the same, taken through the line $\alpha\alpha$, Fig. 6.

The object of this invention is to facilitate 25 the ornamentation of finger-rings and other articles of jewelry.

The invention consists in a finger-ring made with separate side pieces, having grooves in their inner sides to receive the shank of the 30 ring, and grooves in their outer sides, in which are inserted separate ornamental strips or bars, whereby the side pieces can be formed in a solid piece, and the ring and side pieces can be polished or lapped before the strips are introduced, and the strips may also be ornamented before they are applied to the ring, as 35 will be hereinafter fully described.

A is the head of a ring, to the side edges of which are secured the ends of the shank B. C 40 are the side pieces, each of which is made in one piece, and has a groove, D, in its inner surface to receive and fit upon the shank B, where it can be secured in place by a little solder placed in the bottom of the said groove D, so 45 that the side pieces can be readily and economically applied, and there will be no solder at the surface of the ring. In the outer sides of the side pieces, C, are formed dovetailed grooves E, into which are fitted strips F, the 50 exterior surface of which may be engraved or otherwise ornamented prior to insertion within the grooves E. For the economical formation of jewelry the strips may, if desired, be made

in long bars, and ornamented either by hand-engraving or by machine, after which the bars 55 may be cut into suitable lengths and then inserted in the grooves of the ring. With this construction the side pieces, C, can be made separate, applied to the shank B, and polished or lapped in connection with the head A and 60 the said shank B, and can then have the strips F inserted, so that the engraving or other ornamentation of the strip F will not be affected by lapping the ring. The strips F can be inserted in inclined directions, as shown in Fig. 65 2, or lengthwise with the shank, or crosswise with the said shank, as may be desired.

Although my invention is herein shown as applied for use on finger-rings, it will readily be understood that it may also be used with 70 equal facility in the production of all kinds of jewelry in which it is desired to execute the lapping or polishing of the body of the article without injury to the special ornamentation thereof.

Having thus described my invention, I claim as new and desire to secure by Letters Patent—

1. A finger-ring having its ornamental side pieces made separate from the shank and head and provided with grooves in their inner surfaces to receive the said shank, and rigidly secured thereto, substantially as herein shown and described.

2. The side pieces of a ring or other article of jewelry, constructed with grooves in their inner surfaces to receive the shank, and with grooves in their outer surfaces to receive ornamental strips, substantially as herein shown and described.

3. The combination, with the grooved side 90 pieces, C, of the ornamental strips, substantially as herein shown and described, whereby the surfaces of the ring or other jewelry and of the strips can be independently finished, as set forth.

4. The combination, with the shank B, of the side pieces, C, having their inner surfaces provided with the grooves D and their outer surfaces with the dovetail grooves E, and the ornamental strips F, fitting in said grooves E, 100 substantially as herein shown and described.

HEINRICH HENRICH.
